UNITED STATES PATENT OFFICE.

ARTHUR RONALD TRIST, OF LONDON, ENGLAND.

PISTON, PLUNGER, AND THE LIKE.

1,234,972.

Specification of Letters Patent. Patented July 31, 1917.

Application filed March 22, 1916. Serial No. 35,753.

To all whom it may concern:

Be it known that I, ARTHUR RONALD TRIST, subject of the King of Great Britain and Ireland, residing at Coronation House, 5 4 Lloyds avenue, in the city of London, England, have invented new and useful Improvements in and Relating to Pistons, Plungers, and the like, of which the following is a specification.

10 This invention relates to improvements in pistons, plungers and the like of the type in which a fibrous packing is employed to prevent leakage and has for its object the provision of means whereby a piston or 15 plunger is produced having a very high volumetric and mechanical efficiency as compared with known pistons or plungers and in which automatic compensation for wear is rendered possible within wide limits 20 while at the same time the cost of manufacture and up keep is reduced to a very low amount.

The invention consists in the arrangement in the working surface of the piston or 25 plunger of a ring or rings of fibrous or other elastic packing material normally maintained in position by spring pressure the said spring pressure allowing of expansion and contraction of the packing due to 30 internal changes in the physical structure and being augmented to a more or less extent by the working pressure against which the active end of the piston is operating.

In order that the invention may be the 35 better understood I will now proceed to describe the same in relation to the accompanying drawing, reference being had to the letters and figures marked thereon. Like letters refer to like parts in the various 40 figures, in which:—

Figure 1 is an elevation of a ring constructed in accordance with my invention.

Fig. 2 is a section thereof.

Fig. 3 is a section illustrating one method 45 of construction and showing its laminar form.

Fig. 4 is an elevation partly in section showing a single acting piston with one of my rings in position.

50 Fig. 5 is an elevation partly in section showing a double acting piston with two of my rings in position.

Referring to Figs. 1 and 2 which illustrate a ring a constructed in accordance 55 with my invention by way of example said ring a having a cross section of substantially

rectangular form the greatest dimension b of the rectangle being parallel to the axis $c c$ of the ring a . Parts $d d$ of the top and bottom inside edges of the section are removed (see Fig. 3) and bevels $e e'$ are provided in place thereof. The outer or working face f of the ring a is divided by a groove g which is disposed substantially in the middle of the face f and in which if so desired lubricating material can be inserted while to obviate any hoop stress in the ring a during use a conduit h (shown dotted in Fig. 2) can be provided from the said groove so as to directly communicate with the interior of the ring a .

This ring a may be of laminar construction as shown in Fig. 3 and it has been found that the best results are obtained when layers i of fibrous or metallic fabric 75 are embedded in a matrix of cementitious or vulcanizable material k and vulcanized in position when a vulcanizable material is employed. The layers i are preferably so disposed that the edges i' of the said fabric 80 provide the working surface f of the ring.

I have found that the following relative dimensions give satisfactory results with ordinary pressures such as 100 lbs. to 600 lbs. per sq. in.; but it is obvious that considerable modifications may be effected without departing from the invention. Taking the width b as a unit, the width of the end surface d' equals $\frac{1}{2} b$, the width of the interior surface a' equals the width of the groove g which equals $\frac{1}{3} b$, the depth of the groove g equals $\frac{1}{8} b$ and the total thickness of the section equals $\frac{1}{2} b$.

A single acting piston adapted to deal with pressure as indicated by the arrow 4 95 is illustrated in Fig. 4 and is provided with a fixed abutment l having an annular surface l' adapted to conform with and support one of the end surfaces d' and the bevel surface e of the ring a and a member m axially movable relative to the fixed abutment l , the said member m having an annular surface m' adapted to engage with the bevel surface e' , the other end surface d' and the remainder a' of the interior surface of the ring a . The movable member m is maintained in place by means of the spring n which abuts against the nut n' carried by the projection l^2 of the fixed abutment l the said spring n exerting sufficient 100 pressure to hold the ring a in position and expand it so that the said ring a closely 105

contacts with the cylinder o at all parts of its working face.

In this construction it will be seen that the working pressure can pass through the 5 passage m^2 to the interior surface of the member m and thus effect a partial counter balance thereby more or less relieving the ring a of the resultant pressure upon the exterior surface of the member m , due to the 10 working pressure.

A double acting piston is illustrated in Fig. 5 and has two rings a with their respective abutments l and movable members m , associated in opposition to each 15 other, the said movable members m being maintained in operative position by springs n , and to admit pressure from the alternate working ends of the piston to the space between the movable members m so as to 20 permit of freedom of operation of said members m an automatic valve p is provided the said valve p being adapted to simultaneously prevent passage of fluid from one side 25 of the piston to the other through the intervening space. In exceptional circumstances the rings a may be supplemented with duplicate rings acting in tandem therewith a sufficient number of duplicate rings being provided at each end of the piston if it is 30 double acting as may be necessary to safeguard against leakage.

Owing to the very high volumetric efficiency possible when a piston constructed according to this invention is used in association with a cylinder and also the very 35 high mechanical efficiency obtainable due to its frictionless properties it is particularly adapted for use in regulating apparatus due to its lack of leakage and its capability of 40 dealing with very high and very low or even negative pressures without adjustment.

I claim:

1. A piston or the like provided with an annular groove in its periphery having beveled surfaces on its side walls, two axially spaced packing rings positioned within the piston groove at the opposite sides thereof, each of the said rings having oppositely beveled interior faces, one of which contacts 45 with the adjacent beveled face of the piston groove, and two relatively spaced abutment members mounted within the said groove between the packing rings and having beveled side faces for contact with the other beveled 50 faces of the adjacent rings, the said abutment members being constructed so as to present adjacent inner surfaces of comparatively large area and the piston being provided with a fluid conduit extending be- 55 tween the inner part of said groove and the exterior of the piston to admit working pres- 60 sure to the space between the abutment members.

2. A piston or the like provided with an annular groove in its periphery having 65 beveled surfaces on its side walls, two axially spaced packing rings positioned within the piston groove at the opposite sides thereof, each of the said rings having oppositely beveled interior faces, one of which contacts 70 with the adjacent beveled face of the piston groove, two relatively spaced abutment members mounted within the said groove between the packing rings and having beveled side faces for contact with the other 75 bevel faces of the adjacent rings, the said abutment members being constructed so as to present adjacent inner surfaces of comparatively large area and the piston being provided with a fluid conduit extending be- 80 tween the inner part of said groove and the exterior of the piston to admit working pressure to the space between the abutment members, and independent resilient means interposed between the abutment members 85 for exerting expanding force upon the same.

3. A piston or the like provided with an annular groove in its periphery having beveled surfaces on its side walls, two axially spaced packing rings positioned within the piston groove at the opposite sides thereof, each of the said rings having oppositely beveled interior faces, one of which contacts with the adjacent beveled face of the piston groove, two relatively spaced abutment members mounted within the said groove between the packing rings and having beveled side faces for contact with the other bevel faces of the adjacent rings, the said abutment members being constructed so as to present adjacent inner surfaces of comparatively large area and the piston being provided with a fluid conduit extending be- 90 tween the inner part of said groove and the exterior of the piston to admit working pressure to the space between the abutment members, each packing ring having an annular groove in its peripheral friction surface and a radial port extending from the groove to the inner surface thereof, the piston being provided with conduits leading from the groove therein to the said ring ports to establish communication between the ring and piston grooves.

In testimony whereof I have signed my name to this specification in the presence of two subscribing witnesses.

ARTHUR RONALD TRIST.
